ATTORNEY

UNITED STATES PATENT OFFICE.

WILLIAM H. SLAYTON, OF SAN FRANCISCO, CALIFORNIA, ASSIGNOR TO AMERICAN CARBURETER COMPANY, OF VANCOUVER, WASHINGTON, A CORPORATION.

CARBURETOR VALVE.

Application filed April 3, 1922. Serial No. 548,994.

To all whom it may concern:

Be it known that I, WILLIAM H. SLAYTON, a citizen of the United States, residing at San Francisco, county of San Francisco, 5 State of California, have invented certain new and useful Improvements in Carburetor Valves; and I do declare the following to be a full, clear, and exact description of the same, reference being had to the accompanying drawings, and to the characters of reference marked thereon, which form a part of this application.

This invention relates to improvements in carburetors, and is especially intended to 15 be an improvement over that type of carburetor shown in my co-pending application filed July 25th, 1921, Serial No. 487,266.

The principal object of the present invention is to provide a carburetor of the above 20 identified type, in which the fuel in the bowl as well as the air drawn into the mixing chamber is maintained in a heated condition, with automatically opened air-admission valves, so arranged with respect to 25 the fuel-jet members that the air will be drawn in practically all around the same, and will thus mingle more intimately with the fuel charge, the opening of the valves being had by reason of the suction of the 30 engine.

These air valves are entirely automatic in 35 action and once set are not intended to be disturbed or intermittently adjusted, and hence are not provided with any hand-moving or control means, since when an engine to which my carburetor is attached is once running, the interior of the carburetor, through which the air must pass to reach 40 the engine, is heated to the same degree winter or summer.

Another object of my invention is to make the air valves so that they may be removed and replaced by others of different capacity, since this permits of a single stock 45 size of carburetor being used for different sizes of engine and different fuels, in which case the proportionate amount of air relative to the fuel may have to be varied.

A further object of the invention is to 50 produce a simple and inexpensive device and yet one which will be exceedingly effective for the purposes for which it is designed.

These objects I accomplish by means of

such structure and relative arrangement of 55 parts as will fully appear by a perusal of the following specification and claims.

In the drawings similar characters of reference indicate corresponding parts in the several views.

Fig. 1 is an exterior elevation of the carburetor.

Fig. 2 is a sectional elevation of the same.

Fig. 3 is a bottom plan view, and

Fig. 4 is a perspective view of a valve 65 member detached.

Referring now more particularly to the characters of reference on the drawings, the numeral 1 denotes a hollow casing provided with preferably opposed and horizontally 70 disposed orifices 2, one of which is adapted to be connected to a branch from the exhaust gases thus passed into the casing through the other orifice.

Formed integral with the casing and 75 spaced from the walls thereof all around is a cylindrical wall 3 which encloses a central chamber 4 extending vertically of the casing from top to bottom and open at both ends. The lower end is tapped as at 5 while 80 the opening at the upper end is restricted by a flanged neck 6, formed integral with the casing, and which carries a butterfly valve 7 of ordinary construction, the neck being adapted for connection to the intake 85 manifold of an engine.

Screwed into the lower end of the wall 3 and projecting upwardly into the chamber 4 is a fuel-bowl member 8, which above its lower and threaded end is spaced equally all 90 around from the wall 3. This bowl member has a fuel intake pipe 9 at its lower end, the flow from which is controlled by an automatic float-valve structure 10 of standard character. An air passage member 11 leads 95 to the bowl above the float from the atmosphere below the casing to prevent a tendency to vacuum in the bowl.

A plurality of small pipes 12 having interchangeable nozzle-tips 13 extend upwardly around and outside the bowl at intervals and communicate with the lower end of the latter. The latter is capped by a removable cone-shaped hood 14, the rim of which projects somewhat beyond the outer surface of 105 the bowl.

Opening into the bowl and sloping upwardly from the lower end of the casing at

opposite sides of and beyond the tapped portion 5 of the wall 3 are rectangular air passages 15 in which are removably seated frame members 16, which do not interfere with the 5 passageways and in which flap members 17 are pivotally mounted on rods 18 extending lengthwise of the frames or bearings 16 and also at one end through the metal of the casing surrounding and outlining the lower 10 ends of the air passages as at 19.

Strips of leather or other sound absorbing material 20 are placed along the edges of the upper surface of the flaps, which are themselves of metal, so as to eliminate any noise 15 when the flaps strike the back plates of the bearings 16.

These flaps are opened inwardly by the suction of the engine acting through the chamber 4, and when closed rest against the 20 metal of the wall 3 just above its threaded portion 5, where it is cut away to form the passages.

This closing action automatically takes place when the suction ceases by reason of 25 arms 21 and 22 fixed to the outer ends of the rods 18 and projecting upwardly and normally at an angle to each other, and which are connected by a tension spring 23. The arm 21 is longer than the arm 22, and is 30 provided with a plurality of spaced holes 24 arranged lengthwise in the arm, and to any one of which the adjacent end of the spring may be connected so as to alter the normal 35 length of the spring and thus alter its tension at the same time.

It will thus be seen that with the operation 40 of the engine, both flap valves will be opened at the same time, and opposed currents of air, both subjected to heat as soon as they enter the passageways 15, will pass about the bowl and meet, causing swirling currents which will intimately mingle with

the fuel being drawn from the various jets, forming a perfect mixture.

By reason of the flap-valve frames being 45 removable, frames of different thicknesses, thereby altering the size of the flaps carried thereby, may be inserted in a single stock size of casing member without necessitating the air passages themselves being made of 50 different sizes.

From the foregoing description it will readily be seen that I have produced such a device as substantially fulfills the objects of the invention as set forth herein. 55

While this specification sets forth in detail the present and preferred construction of the device, still in practice such deviations from such detail may be resorted to as do not form a departure from the spirit of the 60 invention, as defined by the appended claims.

Having thus described my invention, what I claim as new and useful and desire to secure by Letters Patent, is:—

1. An air valve structure for carburetor casings having an air passage opening into the interior thereof, comprising a removable frame member adapted to fit into said passage, a valve member for closing the passage positioned in the frame, and a common 70 means for pivotally mounting the valve and for holding its frame in position relative to the casing.

2. An air valve structure for carburetor casings having an air passage opening into the interior thereof, comprising a removable frame member adapted to fit into said passage, a valve member for closing the passage positioned in the frame, and a rod turnably 75 passing through the frame and the adjacent 80 chamber casing walls and on which the corresponding valve is mounted.

In testimony whereof I affix my signature.
WILLIAM H. SLAYTON.
